(57) **CLAIM**

I claim the ornamental design for a receptacle for holding cooking grease and oil, as shown and described.

DESCRIPTION

FIG. 1 is a front perspective view of a receptacle for holding cooking grease and oil, showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The even spaced broken lines showing portions of a receptacle for holding cooking grease and oil are for the purpose of illustrating environmental structure and form no part of the claimed design.

The dash-dot broken lines in the drawing views define the bounds of the claimed design and form no part thereof.
